FLOOR MOUNTED FIXTURE FOR PERMANENTLY INSTALLED VACUUM CLEANING SYSTEMS

David H. Hunt, Simsbury, and Robert W. Richardson, West Hartford, Conn., assignors to The Spencer Turbine Company, Hartford, Conn., a corporation of Connecticut

Filed Nov. 5, 1959, Ser. No. 851,061

7 Claims. (Cl. 15—310)

This invention relates to a floor mounted fixture for permanently installed vacuum cleaning systems, and more particularly to improvements in fixtures of the type shown in U.S. Patent No. 2,791,792 dated May 14, 1957.

Fixtures of the patented type available at the present time generally include a hollow, bowl-shaped base portion which is adapted to be mounted in the floor of a building and is provided at its lower end with an outlet for attachment to the piping of a conventional vacuum cleaning system. A floor plate is mounted on the top of the base portion for disposition flush with the floor surface and contains an elongated inlet slot and a tubular socket for receiving the coupling of a vacuum cleaner hose, both the slot and the socket being provided with removable covers for preventing the passage of air therethrough when the fixture is not in use.

When the vacuum producer of the system is in operation and the cover is removed from the inlet slot, air is drawn therethrough at high velocity and dust and debris gathered from the floor may easily be disposed of by sweeping it into the slot. Mops and other cleaning appliances such as dust cloths, blackboard erasers and the like may also be quickly and thoroughly cleaned by passing them back and forth over the slot. When it is desired to use a hose-equipped cleaning tool for a cleaning operation, it is only necessary to remove the cover from the socket in the floor plate and insert the hose coupling therewith. In such cases, the inlet slot is preferably closed so that all of the air drawn into the fixture passes through the cleaning tool to thereby produce maximum suction at the nozzle or cleaning head of the tool.

In vacuum cleaning systems in large or multiple story buildings having a considerable number of floor mounted fixtures, it is necessary to provide a vacuum producer of high capacity to permit the use of several of the fixtures simultaneously. As a result, when only one or two of the fixtures are in use, the velocity of the air flowing therewith is abnormally high because said fixtures are subjected to the full suction force of the vacuum producer. This is not objectionable when a hose-equipped cleaning tool is being used since the increased suction provides greater cleaning efficiency. However, it has been found that air flowing into the inlet slot at an abnormally high velocity sometimes causes a loud, high-pitched, whistling noise which is extremely annoying to persons occupying the building, particularly when such fixtures are installed in schools, hospitals or apartment buildings. The excessive suction thus created also makes it difficult to pass mops or other cleaning articles over the inlet slot since they are drawn tightly against the floor plate.

It is therefore an object of this invention to provide a fixture of the above-mentioned type having means therein to restrict the flow of air through the inlet slot to prevent whistling, but which means will not interfere with the flow of air through the hose socket.

A further object of the invention is to provide a fixture having means therein for reducing the area of the air

2

outlet of the fixture to thereby cut down the air-flow through the inlet slot, but which means is rendered ineffective when the hose socket is being used.

Another object of this invention is to provide a fixture 5 having a restricting member on the cover for the hose socket which restricts the air outlet of the fixture and thereby reduces the air-flow through the inlet slot, but wherein said restricting member is removed from the outlet when the socket cover is removed to allow full flow 10 of air through said socket.

A still further object of the invention is to provide restricting means which are adapted for installation in existing types of fixtures to prevent whistling.

Further objects and advantages of this invention will be 15 more clearly understood from the following description and the accompanying drawing in which:

Fig. 1 is a plan view of a fixture embodying the present invention with the covers for the inlet slot and hose socket in place.

20 Fig. 2 is a side view of said fixture, in central vertical section, clearly illustrating its construction.

The floor mounted fixture shown in the drawing is generally similar to that shown in Patent No. 2,791,792 referred to above and comprises a fixture body 5 including a hollow, bowl-shaped base portion 6 having an annular side wall and a bottom wall defining a chamber 7 therein which is open at its upper end. Said base is adapted to be imbedded in a concrete floor of a building and is provided with radial ears 8 which facilitate positioning of the base before the floor is poured. An integral, centrally located, tubular stem 9 depends from the bottom wall of the base 6 and provides an air outlet 9-a from the chamber 7. Said stem is externally threaded to permit attachment of the fixture body to the permanently installed piping of a conventional vacuum cleaning system.

A substantially square floor plate 10 is fastened to the upper edge of the base 6 by screws 11 and forms the top wall of the chamber 7; said plate being preferably disposed flush with the surface of the floor in which the fixture is mounted. The floor plate is provided with a depending tubular boss 12 providing a socket 13 communicating with the chamber 7 and adapted to detachably receive the conventional coupling provided on the 45 end of the hose of a vacuum cleaning tool such as a floor or wall brush. The socket 13 is normally closed by a removable, flush-fitting cover 14 which rests on an annular sealing gasket 15 seated in the wall of the socket. At one side of the socket 13, the floor plate 10 is provided with an elongated inlet slot 16 which also communicates with the chamber 7, and said slot is normally closed by a flush-fitting cover 17 which rests on a sealing gasket 18 that is seated in the wall of the slot.

It will be understood that in fixtures of the conventional 55 type such as above described, air-flow through either the socket 13 or the inlet slot 16 is unrestricted when their respective covers are removed. This is most desirable when the socket is in use since it provides maximum suction through the cleaning tool. However, when the 60 socket is closed and the inlet slot is open, air flowing through the slot at an abnormally high velocity can produce an annoying whistling noise as hereinbefore mentioned.

In accordance with the present invention, therefore, 65 we provide for insertion into the chamber 7 of the fixture body 5 a baffle 19 in the form of an inverted cup-shaped member including an upper plate portion 20 and an annular depending rim 21 having a gasket 22 around its lower edge which rests on the bottom wall of the base 6 to effect an air-tight seal around the edge of the baffle. The plate portion 20 of the baffle has a short

tubular projection 23 of circular cross-section depending therefrom which provides an air outlet 24 from the portion of the chamber 7 about the baffle that is disposed coaxially with the socket 13. The upper marginal edges of the tubular projection 23 are preferably smooth and rounded to insure proper air-flow into the outlet 24 and to eliminate any sharp edges which would be liable to catch dust or other foreign matter drawn into the fixture.

The cover 14 for the socket 13 has a tubular restricting plug 25 projecting axially from the underside thereof which, when the cover is in place, extends axially through the said socket and the outlet 24 as shown in Fig. 2. The restricting plug 25 is smaller in diameter than the outlet 24 to provide an annular space 26 between the plug and the wall of the outlet through which a limited amount of air may flow in response to the negative pressure created by the vacuum producer.

It will be understood from the above description that when the socket cover 14 is in socket closing position, as shown in Fig. 2, and the inlet slot 16 is open, the airflow through the inlet slot is greatly reduced by the presence of the restricting plug 25 in the outlet 24. This naturally reduces the velocity of the air flowing through the inlet slot and thereby eliminates the whistling noise previously experienced. Furthermore, mops and other cleaning articles will not be drawn tightly against the floor plate although sufficient suction will still be present to remove the dust and dirt imbedded therein.

When the socket cover 14 is removed to permit insertion of a hose coupling into the socket 13, the restricting plug 25 will be removed therewith and from the outlet 24 to allow the unrestricted flow of air through said socket and the cleaning tool to which said hose is attached.

If dirt or other foreign matter drawn through the slot 16 should clog the annular space 26, it may easily be gotten rid of by momentarily lifting the cover 14 to remove the restricting plug 25 from the outlet 24 and thereby permit said foreign matter to be sucked through said outlet 24 and into the vacuum cleaning system.

It will be evident that the baffle 19 may be eliminated by forming the fixture base 6 with the stem 9 disposed in axial alignment with the socket 13 and extending the restricting plug 25 into the outlet 9-a in said stem. While this construction would operate as above described, it is advantageous to have the stem located centrally of the fixture base since this facilitates installation of the fixture. In addition, our invention permits a manufacturer to produce one type of a fixture which may be used with or without the baffle 19 and the restricting plug 25 as required.

We claim:

1. A fixture for a vacuum cleaning system including a fixture body having a chamber therein and an outlet opening of predetermined area for establishing communication between said chamber and said system, said body having a dirt-receiving inlet opening and a socket for a hose coupling formed therein which both provide communication between the atmosphere and said chamber, a removable cover for said inlet opening, a separate removable cover for said socket, and a restricting member secured to the cover for said socket and having a portion positioned to reduce the effective area of said outlet opening when said socket cover is in socket closing position to restrict the flow of air through said inlet opening when its cover is removed.

2. The subject matter set forth in claim 1 wherein said restricting member is adapted to be removed from said fixture body through said socket when the socket cover is removed to permit full flow of air through said outlet opening.

3. A fixture for a vacuum cleaning system including a fixture body having a chamber therein and an outlet open-

ing for establishing communication between said chamber and said system, said body having a dirt-receiving inlet opening and a socket for a hose coupling formed therein which both provide communication between the atmosphere and said chamber, said socket and said outlet opening being axially aligned, a removable cover for said inlet opening, a separate removable cover for said socket, and a restricting member extending axially from said socket cover and having a portion positioned relatively to said outlet opening to restrict the flow of air therethrough when said socket cover is in socket closing position, said restricting member being removed from restricting position upon removal of said socket cover to permit maximum air flow through said outlet opening.

5. A fixture for a vacuum cleaning system including a hollow fixture body having a chamber therein, a baffle in said body dividing said chamber into a first section and a second section, said fixture body having a dirt-receiving inlet opening and a socket for a hose coupling formed therein which both provide communication between the atmosphere and said first section of the chamber, said body having a main outlet opening therein communicating with said second section of the chamber, said baffle having an opening therein providing communication between said first and said second sections of the chamber, a removable cover for said inlet opening, a separate removable cover for said socket, and a restricting member in said body positioned to reduce the effective area of the opening in said baffle to thereby reduce the volume of air flowing through said inlet opening when its cover is removed.

6. The subject matter set forth in claim 5 wherein said restricting member is attached to the cover for said socket and is disposed in restricting position when said cover is in socket closing position, and said restricting member is adapted to be removed from restricting position when said socket cover is removed from said socket.

7. The subject matter set forth in claim 5 wherein the opening in said baffle is in axial alignment with said socket, and said restricting member extends axially from said socket cover into said opening and is of a smaller size than said socket, whereby said restricting member is adapted to be removed from said fixture through said socket when said socket cover is removed.

8. In a fixture for a vacuum cleaning system comprising a hollow fixture body including a top wall and a bottom wall defining a chamber therein, said top wall having a dirt-receiving inlet opening and a socket for a hose coupling formed therein both communicating with said chamber, and said bottom wall having an outlet opening therein for establishing communication between said chamber and said system; the improvement which comprises, a separate baffle disposed in said chamber, said baffle being in the form of an inverted, cup-shaped member disposed with its lower edge portion in substantially air-tight engagement with the bottom wall of said body and thereby dividing said chamber into an upper section in communication with said inlet opening and said socket and a lower section in communication with said outlet opening, said baffle having an opening therein in axial alignment with said socket, and a restricting member secured to said socket cover and extending therefrom into the opening in said baffle, said restricting member reducing the effective area of said opening whereby the flow of air through said inlet opening is reduced when its cover is removed.
